UNITED STATES PATENT OFFICE.

EARL C. AKERS, OF PORT HURON, MICHIGAN.

CURRENT-MOTOR.

1,121,447.

Specification of Letters Patent. Patented Dec. 15, 1914.

Application filed October 23, 1913. Serial No. 796,770.

To all whom it may concern:

Be it known that I, EARL C. AKERS, a citizen of the United States of America, residing at Port Huron, in the county of St. Clair and State of Michigan, have invented certain new and useful Improvements in Current-Motors, of which the following is a specification, reference being had therein to the accompanying drawings.

10 This invention relates to current motors of a type available for use in rapidly running, open streams, and to an arrangement of the propelling members, blades or buckets whereby not only the impinging effect of 15 the water is obtained, but also the weight effect of a considerable portion of trapped water acting on several propelling members through a considerable space of time and with even torque on a driving shaft, or 20 shafts.

The invention consists in the matters hereinafter set forth, and more particularly pointed out in the appended claims.

In the drawings, Figure 1 is a view in 25 side elevation of a device that embodies features of the invention, in operative position. Fig. 2 is a view in end elevation thereof, with the buckets or propelling members empty; Fig. 3 is a view in detail from above, 30 of a propelling blade, the hanger therefor and the guide rolls. Fig. 4 is a view in front elevation of the blades and adjacent parts; Fig. 5 is an enlarged view in detail 35 of guide members for a blade and a spring for maintaining them in position, and Figs. 6 and 7 are views in detail of a positive latch and guard rail for holding a blade in operative position.

Referring to the drawings, a pair of 40 shafts 1, from either or both of which power may be taken, are suitably journaled in parallel, substantially horizontal position on a properly proportioned main frame 2 adapted to be placed in the bed of a running stream as indicated. Pairs of similarly disposed 45 sprocket wheels 3 are secured in alined position on the shafts 1 and are connected by flexible means such as sprocket chains 4. At intervals, cross members 5 connect the chain and form pivots on which substantially rectangular slightly curved blades 7 are suspended by suitably disposed hangers 8. The wheels, chain and main frame are so arranged that the blades 7 clear 50 the shafts 1 when passing thereover and are completely submerged beneath the level

of the stream when running along the lower limb of the path described by the chain. Properly disposed guide rails 9 support the chain between the wheels when above the 60 frame, corresponding guides 10 below the wheels prevent the chain from sagging along the lower limb of the path.

At each lower corner of each blade, a pair of spaced, parallel guide rolls 11 are 65 journaled on studs 12 of a rock arm 13, carried by the extremities of rods 14 journaled in a pair of hangers 15 on the lower margin of the blade. The rock arms 13 of each blade are normally held at substantially 70 right angles to the vertical plane of the blade by means of suitably disposed spring members 16. A track 17 on the main frame in parallel relation to the guide members 10 on each side of the frame, has an upwardly extending oblique portion 18 on the upstream side with a rounded upper end so disposed that as the blades pass downwardly into the water over the wheel the rolls 11 are pressed against the underface 80 of the track by the action of the water and maintain the blades in effective position, holding them substantially vertical to the current of the stream while the blades are traversing the guides 10 on the track 17. 85

If desired each blade may have positive means for locking or holding it in operative position. Such construction is shown in Figs. 6 and 7 in which a blade 20 has a rock arm 21 at each lower corner with a pair 90 of guide rolls 22 on each. A spring 23 yieldingly holds the rolls against the track member 17. When under running the track 17 with the blades assuming the proper operative position, a latch bar 24 that is normally retracted by a spring 25 is thrown into locking engagement with the lock arm 21 by the contacting of the roll 26 on the latch with a guide rod 27. This positively prevents the blade from tilting until the rail 100 27 is cleared.

In operation the water that impinges against each blade as it enters the current or stream causes the forward movement of blades along the lower guides and tracks 105 while the weight of the water trapped between consecutive blades, urges the blades along as the water moves down stream. Thus the several pockets of water between the several blades of the device that are 110 always submerged, aid the impact effect of the current in operating a motor and there-

by are especially adapted to utilize a stream which has a comparatively large volume and moves at slow speed. The parts are so disposed as to be readily assembled and taken care of, and do not tend to get out of adjustment and are efficient. Either of the shafts or both may be operatively connected to any mechanism to be driven.

Obviously, changes in the detail of the 10 construction may be made without departing from the spirit of my invention and I do not care to limit myself to any particular form or arrangement of parts.

What I claim is:—

15. A current motor comprising a main frame, a pair of rotatable shafts journaled in parallel, spaced relation therein, sprocket wheels on the shafts, propeller blades articulated at the upper portions thereof to 20 travel around the shafts with the lower portions pendant, and yieldingly secured guiding members on the blades coöperating with the main frame to maintain the blades in operative position when submerged.

25. A current motor comprising a main frame adapted to be partially submerged in a running stream, a pair of shafts journaled thereon in parallel, spaced relation, propeller blades articulated at the upper 30 portions in an endless series encircling the shafts, wheels on the shafts engaged and driven by the blade series, and means on each blade yieldingly engaging the frame when the blade is submerged and coöperating therewith to maintain the blade substantially perpendicular to the current of a stream.

35. A current motor comprising a main frame, adapted to be partially submerged in a running stream, track members on the submerged portion of the frame arranged substantially parallel to the course of a stream in which the frame may be set, a pair of spaced, parallel shafts transverse to 40 the track members journaled on the frame, sprocket wheels on the shafts, endless flexible connections running over companion pairs of wheels, propelling blades pivoted near the upper margins to the chains to 45 swing therefrom, and guiding members on the lower portions of the blades yieldingly engaging the tracks intermittently and co-operating therewith to maintain the blades in operative position when they are 50 submerged.

55. A current motor comprising a main frame, adapted to be partially submerged in a running stream, track members on the submerged portion of the frame arranged substantially parallel to the course of a stream in which the frame may be set, a pair of spaced, parallel shafts transverse to 60 the track members journaled on the frame, sprocket wheels on the shafts, endless flexible connections running over companion 65

pairs of wheels, propelling blades pivoted near the upper margins to the chains to swing therefrom, pairs of guiding rolls on the lower blade corners, and spring members yieldingly defining the position of the 70 rolls in relation to the blades, and coöperating with the rolls and tracks to maintain the blades in operative position when submerged.

75. A current motor comprising a main frame, adapted to be partially submerged in a running stream, track members on the submerged portion of the frame arranged substantially parallel to the course of a stream in which the frame may be set, a pair of spaced, parallel shafts transverse to 80 the track, members journaled on the frame, sprocket wheels on the shafts, endless flexible connections running over companion pairs of wheels, propelling blades pivoted near the upper margins to the chains to swing therefrom, a rock shaft on the lower portion of each blade, a pair of rock arms on the extremities of the shaft adapted to 85 underrun the track members when the blade is submerged, and spring members connecting the rock shaft and blade for maintaining the rock arms in substantially perpendicular relation to the blades.

90. A current motor comprising a main frame, adapted to be partially submerged in a running stream, track members on the submerged portion of the frame arranged substantially parallel to the course of a stream on which the frame may be set, a pair of spaced, parallel shafts transverse to the track, members journaled on the frame, sprocket wheels on the shafts, endless flexible connections running over companion pairs of wheels, guide members for the 95 chains between the sprocket wheels, propelling blades pivoted near the upper margins to the chains to swing therefrom, pairs of guiding rolls on the lower blade corners, and spring members yieldingly defining the 100 position of the rolls in relation to the blades, and coöperating with the rolls and tracks to maintain the blades in operative position 105 when submerged.

110. A current motor comprising a main frame, adapted to be partially submerged in a running stream, track members on the submerged portion of the frame arranged substantially parallel to the course of the stream in which the frame may be set, a pair of spaced, parallel shafts transverse to the track members journaled on the frame, sprocket wheels on the shafts, endless flexible connections running over companion 115 pairs of wheels, guide members for the chains between the sprocket wheels, propelling blades pivoted near the upper margins to the chains to swing therefrom, a rock shaft on the lower portion of each blade, a pair of rock arms on the extremities of the 120

125

shaft adapted to underrun the track members when the blade is submerged, and spring members connecting the rock shaft and blade for maintaining the rock arms in substantially perpendicular relation to the blades.

In testimony whereof I affix my signature in presence of two witnesses.
